Patented June 6, 1972

223,777

DECORATIVE GRILLE

Patrick L. Zampetti, Cranford, N.J., assignor to
Construction Specialties, Inc., Cranford, N.J.

Filed Dec. 30, 1969, Ser. No. 20,698

Term of patent 14 years

Int. Cl. D25—01

U.S. Cl. D54—2

FIG. 1

FIG. 2

FIG. 3

FIG. 4

FIG. 5

FIG. 6

FIG. 1 is a front elevational view of a grille showing my new design;

FIG. 2 is a plan view of the grille shown in FIG. 1;

FIG. 3 is a front elevational view of a grille illustrating modifications of my design;

FIG. 4 is a plan view of the grille shown in FIG. 3;

FIG. 5 is a front elevational view of a grille showing further modifications of my design; and

FIG. 6 is a plan view of the grille shown in FIG. 5.

I claim:

The ornamental design for a decorative grille, as shown and described.
